(57) **CLAIM**

The ornamental design of an automobile dashboard and console, as shown and described.

DESCRIPTION

FIG. 1 is a first perspective view of an automobile dashboard and console showing our new design;

FIG. 2 is a second perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and,

FIG. 8 is a right side elevation view thereof.

The broken lines immediately adjacent the shaded areas represent the bounds of the claimed design while other broken lines are directed to environment and/or are for illustrative purposes only. The broken lines form no part of the claimed design.
